Primary Examiner — Kevin K Rudzinski*Assistant Examiner* — Xavier Marti-Santos(74) Attorney, Agent, or Firm — Michael Best & Friedrich LLP(57) CLAIM

The ornamental design for furniture legs as shown and described.

DESCRIPTION

FIG. 1 is a perspective view of the furniture legs showing our new design.

FIG. 2 is a front view of the furniture legs of FIG. 1.

FIG. 3 is a rear view of the furniture legs of FIG. 1.

FIG. 4 is a first side view of the furniture legs of FIG. 1.

FIG. 5 is a second side view of the furniture legs of FIG. 1; and,

FIG. 6 is a top view of the furniture legs of FIG. 1. The broken lines in the figures are for the purpose of illustrating portions of the furniture legs, which form no part of the claimed design.

1 Claim, 6 Drawing Sheets(56)
